DISPENSING AND SLICING MACHINE

Filed August 4, 1925 2 Sheets-Sheet 2

UNITED STATES PATENT OFFICE.

ROBERT L. WALKER, OF DAVIS, OKLAHOMA.

DISPENSING AND SLICING MACHINE.

Application filed August 4, 1925. Serial No. 48,100.

This invention relates to an improved machine adapted for store and lunchroom use, the same being adapted to slice and dispense rolls, buns, or the like.

5 The invention has more particular reference to a machine adapted to be placed upon a counter or the like, to render the contents readily visible to customers, there being novel means for sliding a roll or bun, and 10 then ejecting it, so that it may be dispensed in a sanitary and safe manner.

More specifically, the invention has reference to a relatively stationary container, provided with a sight glass, through which the 15 contents may be inspected, there being a rotor mounted for rotation in this container, and this rotor being provided with a plurality of circumferential pockets, in which the articles to be cut and dispensed are 20 placed.

Another feature of the invention is an ejecting and slicing compartment which is located below the container, this compartment having a door, through which the 25 sliced article is projected.

Other features and advantages will become apparent from the following description and drawings.

In the accompanying drawings, forming a 30 part of this application, and in which like numerals are employed to designate like parts throughout the same:

Figure 1 is a front elevation of a dispensing and slicing machine constructed in 35 accordance with the present invention.

Figure 2 is a section, taken approximately upon the plane of the line 2-2 of Figure 1, looking downwardly.

Figure 3 is a central vertical section 40 through the container.

Figure 4 is a central longitudinal section through the ejecting and slicing container shown in Figure 5, the section being approximately upon the plane of the line 4-4 of 45 Figure 5.

Figure 5 is a central vertical section through Figure 4, and

Figure 6 is a perspective view of the ejecting block.

50 In the drawing, the reference character 1 designates a base, 2 denotes a container, and 3 represents an elongated box which is interposed between and connected with the base and container. Considering the container first, it will be seen that it is formed in one side with a vertically elongated opening,

covered by the glasswindow 4 to permit the contents to be readily viewed. Mounted for rotation in the container (see Figures 2 and 3) is a rotor 5, comprising a central shaft 60 6 and constructed to provide a plurality of circumferentially spaced cylindrical pockets 7. A hand wheel 8 is adapted to be connected with the upper end of the shaft, for rotating the drum or rotor. The pockets 7 65 are adapted to be brought around into registry with a discharge opening 9 in the bottom of the container. An opening is also formed in the top of the container above the opening 9, and this opening is closed by a 70 cover 10. The article to be dispensed is placed through the covered opening 10 into the various pockets 7 of the drum, as the latter is rotated to bring the pockets into registry with the opening 9, so that the article 75 may drop, by gravity, down through this opening, and into the elongated box 3. To permit the article to drop into it, the box is formed in its top with an opening 11 (see Figure 5). In the bottom, it is provided 80 with an elongated guide slot 12. Slidable in the box, and normally retained at one end of the same is an ejecting block 13, the central portion of which is rabbeted to form a shoulder 14. The opposed side walls of the 85 box are provided with slots 15, through which a slicer, preferably in the form of a saw 16, is slidable. The box is open at its front and this open end is closed by a self closed door 17. As shown more plainly in 90 Figure 5, a wire rod 18 is connected with the block and extends through a guide 19, being formed at its outer end with a handle 20. At this time, I would direct attention to the fact that the box 3 is disposed diagonally with respect to the base 1, for a purpose to be hereinafter set forth.

95 Novel means is employed for simultaneously reciprocating the saw 16, and sliding the block 13, and in this instance, it will be 100 noted that a pulley 21 is carried by the rear end of the box 3, a pulley 22 is mounted on the opposite end of the base. A cord 24 is wound on the drum 23 and the drum is normally rotated and held in a predetermined 105 position by the coiled spring 25, the cord being also connected with the saw 16. Another cord or the like 26 is connected to the opposite end of the saw and is trained over the pulleys 21 and 22 and connected with 110 the aforesaid block 13, as shown in Figure 5.

The operation of the device is as follows:

Rolls, buns, or the like, are placed in the pockets 7 of the rotor. The rotor is now rotated by the hand wheel 8 to bring one of these pockets over top of the discharge opening 9 in the container. The bun may now drop by gravity down into the box 3, to render it ready for slicing. At this time, the bun is fully exposed through the window 4. It is obvious that by grasping the handle 20 and pulling the rod 18, the ejector block 13 will be moved toward the bun. Simultaneously with this sliding of the block, the saw 16, through the medium of the pulleys and cords, will be drawn in a manner to slice through the bun, the sliced article being ejected by the block, so that by opening the door 17, the same may be removed. The spring rotated drum 23 will serve to automatically return the parts to their normal position. It should be observed that the angle of movement of the saw is such, with respect to the path of movement of the ejecting block as to facilitate cutting through comparatively soft and crumbly material.

It is thought that persons familiar with devices of this class will, after carefully considering the description be able to obtain a clear understanding of the invention. For this reason, a more lengthy description is thought unnecessary.

While the preferred embodiment of the invention has been shown and described, it is to be understood that minor changes coming within the field of invention claimed may be resorted to, if desired.

I claim:

1. In a dispensing and cutting machine

of the class described, a box into which the article to be cut is adapted to be dropped, an ejector block slideable in said box, said box being open at one end and said open end being closed by a closure, said box being formed in opposed sides with openings, and a cutter passing through said openings and disposed diagonally with respect to the central axis of said ejector.

2. In a dispensing and cutting machine of the class described, a box into which the article to be cut is adapted to be dropped, an ejector block slideable in said box, said box being open at one end and said open end being closed by a closure, said box being formed in opposed sides with openings, a cutter passing through said openings and disposed diagonally with respect to the central axis of said ejector, a base, means for operating said ejector, and means operated by said operating means for simultaneously actuating said cutter and ejector.

3. In a slicing and dispensing machine of the class described, a base, an elongated box disposed diagonally across the central portion of the base, said box being open at one end for discharge of the cut article and being formed with an opening to permit entrance of the article to be cut, an ejector block slideable in said box, a cutter mounted in said box and disposed for cooperation with said block, an operating rod for said block, and flexible connection between the block and cutter whereby the two are simultaneously operated.

In testimony whereof I affix my signature.

ROBERT L. WALKER.
